UNITED STATES PATENT OFFICE.

ROBERT B. METZNER, OF WHEELING, WEST VIRGINIA.

MINING MACHINE.

Application filed June 11, 1926. Serial No. 115,286.

This invention relates to certain new and useful improvements in mining machines, and while designed particularly for use with pneumatically operated machines employed in the mining of coal, is nevertheless susceptible to use in connection with the mining of various substances.

The primary object of the invention is to provide a machine which has improved means for reciprocating the piston by compressed air and for cushioning the piston at each of the limits of its reciprocating movements.

A further object of the invention is to provide means for effecting gradual and uniform cushioning of the piston at the limits of its strokes and, further, to provide means of the character mentioned which is of simple, economical and compact construction and which is positive and reliable in operation.

A still further object of the invention is to provide cushioning means which is wholly incorporated within the cylinder or cylinders of the machine and which is devoid of parts that project exteriorly of the cylinders.

The invention has still further and other objects which will hereinafter be made apparent, and it resides in the novel construction and combinations of parts which will hereinafter be fully described.

In the drawings—

Figure 1 is a top plan view of the invention, partly broken away and in section;

Figure 2 is a section on line 2—2, Fig. 1.

Figure 3 is a detail sectional view of one of the check valves; and—

Figures 4, 5 and 6 are enlarged sections taken on lines 4—4, 5—5, and 6—6, respectively, of Fig. 2.

Referring to said drawings, 1 designates the frame of the machine, which is here shown as equipped with a pair of relatively parallel cylinders 2 having pistons 3 there-in. Connecting rods 4 are pivoted at their inner ends at 5 to said pistons 3 and at their outer ends to cranks 6 of a crank shaft 7. Said crank shaft is mounted on roller bearings 8 and is provided with cover plates 9 at its ends. The connecting rods 4 and the cranks 6 have ball-bearings 10, while cover plates 12 fastened by screws 13 provide access to the ball-bearings. The cover plates have oiling openings closed by plugs 14.

A gear wheel 15 mounted on the crank

shaft 7 occupies driven relation to a pinion 16 carried by a drive shaft 17, the latter being operated by a motor 18.

A piston rod 19 is slidably in a bearing 20 formed in a hollow tapered extension 21 of a head 22 which is mounted on the front end of the cylinder by means of bolts 23. As illustrated in Fig. 6 of the drawings, keys 24 are attached by means of screws 25 to the piston rod 19 and, in movements of said rod, slide in key-ways provided therefor in the bearing 20, thereby to hold said rod 19 against rotary movement, while permitting said rod to reciprocate unobstructedly. Drills or cutting tools 26 are suitably attached to the outer free ends of the piston rods 19 and may be of any suitable form.

The hollow tapered extension 21 performs a dual function, namely, it provides a bearing for the rod 19 and by virtue of having openings or ports 27 through which air may enter and vent freely, it supplies air to the cylinder 2.

A piston 28 is rigidly secured to the inner end of the piston rod 19, while a piston 29 is provided with a central opening through which the rod 19 extends, the piston 29 having a stuffing box 30. Tie rods 31, shown in Figs. 2 and 4, have opposite shouldered ends which extend through openings provided therefor in the pistons 3 and 29. Nuts 32 are secured to the ends of the rods 31, whereby the pistons 3 and 29 are rigidly connected for movement in unison. The piston 28 is also provided with openings through which the connecting rods 31 freely pass.

The pistons 3 and 29 are provided with check valves 33 and 34, respectively. Since said valves are identical, a description of one will herein suffice for both. Referring to Fig. 3, it will be seen that a chamber 35 is provided for the ball-valve 33, and that said chamber has its inner end registering with a port 36 of reduced diameter, a shoulder being thus formed, upon which a coil spring 37 seats. The other end of the chamber is enlarged and threaded, and seated therein is a plug 38 having extending therethrough a port 39 the inner end of which terminates in a seat 40 for said ball-valve. The spring 37 acts not only to cushion the ball-valve, but also to prevent said valve from assuming closing relation to the port 36.

In operation, the drive shaft 17 is rotated

by the motor 18 driving pinion 16 and thereby the gear wheel 15, effecting alternate reciprocation of the connected pistons 3 and 29. The pistons 3 and 29 form the end walls of an intermediate chamber, the side walls of which are constituted by the cylinder 2. As the pistons 3 and 29 move forward within the cylinder, the check valve 34 of piston 29 is opened and air is permitted to pass therethrough into the space between piston 29 and piston 28. At the same time, the check valve 33 of piston 3 is seated, thereby compressing air between the pistons 3 and 28, which body of compressed air causes the piston 28 to advance with piston 3 and thereby impart to the rod 19 its working stroke. Such body of compressed air at the same time acts to cushion the piston 28 and prevent same from forcibly engaging the piston 3. Upon rearward movement of the piston 3, the valve 33 is unseated and the air compressed between the pistons 3 and 28 escapes through the port 39 in the plug of said piston 3. Since the piston 29 moves with the piston 3, the valve 34 is actuated to seat, following which the air between pistons 28 and 29 is compressed, thereby actuating the rod 19 to move rearwardly in its return stroke.

30. From the foregoing it will be seen that the piston 28 and the thereto attached rod 19 and the cutter 26 are actuated both on the working and return stroke by the resilient bodies of air compressed between opposing faces of piston 28 and the pistons 3 and 29, there being thus provided not only a mean of cushioning each end of each stroke of piston 28, but also means for cushioning the impact of the cutter.

40. What is claimed is—

1. In a mining machine, a cylinder having a tapered hollow extension on its forward end provided with air ports, a piston in the cylinder having a rod journaled in the front end of the extension, a pair of relatively spaced pistons on opposite sides of the first piston, tie rods connecting said pair of pistons and freely movable through the first piston, a rod connected to the rearmost 45 of the pair of pistons, means to reciprocate the rod, and check valves carried by the pistons of said pair whereby, upon reciprocation of said pair of pistons, alternately to compress air between opposite faces of the

first piston and the confronting faces of the 55 pistons of the pair for effecting reciprocation of the first piston and for cushioning the latter both on its advance and return strokes.

2. In combination with a cylinder, a piston therein having a rod, a pair of pistons arranged on opposite sides of the first piston, tie rods rigidly connecting the pair of pistons and freely movable through openings provided therefor in the first piston, a 60 connecting rod attached to the rearmost of the pair of pistons, means to reciprocate the connecting rod, and check valves carried by the pistons of the pair whereby, upon reciprocation of said pair of pistons, alternately to compress air between opposite faces of the first piston and the respective pistons of the pair for effecting reciprocation of the first piston and for cushioning the latter both 65 on its advance and return strokes. 70

3. In a mining machine, a cylinder, a piston in the cylinder having a rod, a pair of relatively spaced pistons disposed on opposite sides of the first piston, means to connect the pair of pistons for movement in 80 unison, reciprocating means for said pair of pistons having connection with the rear piston of said pair, and check valves carried by each of the pair of pistons whereby, upon reciprocation thereof, air will be compressed between the opposed faces of the first piston and the respective pistons of the pair for effecting reciprocation of the first piston and for cushioning both of its strokes. 85

4. In a mining machine, a cylinder having 90 a tapering hollow extension on its forward end provided with air inlets, a piston in the cylinder having a piston rod provided with a bearing in the outer end of said extension, a pair of pistons disposed at opposite sides 95 of the first piston, means connecting the pair of pistons for movement in unison, means to reciprocate said pair of pistons connected to the rear piston of said pair, and a check valve in each of the pair of pistons whereby, 100 upon reciprocation of the latter, air will be compressed between the opposed faces of the first piston and the respective pistons of the pair for effecting reciprocation of the first piston and for cushioning each of the strokes 105 of the latter.

In testimony whereof, I affix my signature.

ROBERT B. METZNER.
